UNITED STATES PATENT OFFICE.

WALTER E. AMBERG, OF CHICAGO, ILLINOIS.

FOLDING-MACHINE.

1,245,421.

Specification of Letters Patent.

Patented Nov. 6, 1917.

Application filed July 11, 1914. Serial No. 850,490.

To all whom it may concern:

Be it known that I, WALTER E. AMBERG, a citizen of the United States, and a resident of Chicago, county of Cook, and State of Illinois, have invented certain new and useful Improvements in Folding-Machines, of which the following is a specification.

My invention relates to improvements in paper folding machines and has special reference to improved devices for folding letter sheets, bills, circulars, and similar articles.

The object of my invention is to provide a machine which shall reduce the necessary expenditure of time and labor in the folding of letter sheets and similar pieces of paper; to provide a simple and durable folding mechanism which shall be easily operable to fold the sheet, either upon parallel lines or upon lines which cross each other at right angles; to provide a sheet folding device of simple construction and relatively low cost, and adapted either for hand or power manipulation, and which shall be suitable for use in business offices and the like for folding letters of correspondence and such like articles for insertion into envelops.

In the folding of letter sheets and similar articles, particularly for insertion into envelops, there are many arrangements and combinations of folds which it is desirable to make, ranging from a single fold forming two leaves to one which includes, first a crosswise fold and then the crosswise folded sheet folded into small compass.

It is a special object of my invention to provide a folding machine wherein and whereby letter sheets and similar articles can be folded in any one of several ways depending upon the size of the sheet, and the dimensions desired for the folded sheet, upon lines at right angles to the first fold, and consisting of one or more of such folds as may be necessary to produce the results desired.

My invention further contemplates the production of a machine or device having a substantially flat surface to receive the sheet to be folded and adapted to fold the sheet crosswise without the necessity of placing any mechanical holder above the sheet, and adapted to fold the crosswise folded sheet at right angles to the first fold and on parallel lines into a compact package and arranged to crease the edges of the folds as the folded sheet is withdrawn from the folding mechanism.

My invention resides in a machine having a flat surface to receive a sheet to be folded, a plate or other flat obstruction having parallel side edges beneath which one portion of the sheet is adapted to be placed and means for forming the end portion or portions over and upon the obstruction or plate and around the edges thereof, and means for finally creasing the fold or folds thus formed to preserve the sheet in its folded condition.

My invention further resides in a machine having a substantially flat surface to receive a sheet to be folded, means for holding the middle portion of the sheet against movement in a direction away from said surface and provided with rotatable members adapted to lift either one or both end portions of the sheet and rotate them around and upon the held portion of the sheet, with means for creasing the edges of the folds thus formed as the sheet is withdrawn from its folded position.

My invention further resides in a machine having a substantially horizontal surface to receive the sheet, stops to retain the sheet against movement on the surface, a rotatable member supporting the end of the sheet opposite to said stops, preferably in inclined elevated position, and adapted to be rotated to fold said end down upon the stopped end and thereby fold the sheet crosswise, said plate in its final position being adapted to form a holder for the middle portion of said folded sheet to retain it in position, and rotatable plates arranged beneath the ends of said folded sheet adapted to raise said ends and fold them over and upon said holder and the middle portion of said sheet, and means for creasing the edges of the several folds as the sheet is withdrawn from its folded position.

My invention also resides in the several features of construction, and the arrangements and combinations of parts, by means of which the above and other objects are attained, and all as hereinafter described and particularly pointed out in the appended claims.

My invention will be more readily understood by reference to the accompanying drawings, forming a part of this specification, and in which:

Figure 1 is a top plan view of a machine illustrating one embodiment of my invention, the several parts being shown in position to receive a sheet of paper to be folded;

- Fig. 2 is a similar view of the machine showing the parts in partly folded condition;
- Fig. 3 is a longitudinal vertical section on the line 3—3 of Fig. 1;
- Fig. 4 is a similar section on the line 4—4 of Fig. 2;
- Fig. 4^a is an enlarged detail side view of one of the sheet stops;
- 10 Fig. 5 is a bottom plan view of the machine as shown in Fig. 1;
- Figs. 6, 7, and 8 are transverse vertical sectional views on the line 6—6 of Fig. 1 showing the operating lever in several different positions;
- Fig. 8^a is an enlarged elevation of the mechanism for operating the side blades;
- Fig. 8^b is a top plan view of the mechanism shown in Fig. 8^a;
- 20 Fig. 9 is an enlarged detail sectional view of the operating mechanism which connects two of the movable shafts in the machine;
- Fig. 10 is a similar view showing the parts in different relative positions;
- 25 Fig. 11 is a detail showing the means of operating the swinging yoke;
- Fig. 12 is a detail vertical sectional view on the line 12—12 of Fig. 2 illustrating the creaser;
- 30 Fig. 12^a is an end elevation of one of the creasing devices;
- Fig. 13 is a transverse vertical sectional view on the line 13—13 of Fig. 2, the side plates being in extended position;
- 35 Fig. 14 is a section similar to Fig. 13 showing the side plates in folded position upon the central plate;
- Fig. 15 is an enlarged detail section on the line 15—15 of Fig. 2;
- 40 Fig. 16 is a section similar to Fig. 15 showing the positions of the frame locking parts just before the frame reaches its final position;
- Figs. 17 to 22, inclusive, illustrate sheets 45 of paper of various relative dimensions which the machine is adapted to fold;
- Figs. 23 to 28, inclusive, are diagrammatical illustrations showing the positions of the plates relatively to the several sheets 50 and illustrating the manner in which the machine folds these sheets;
- Figs. 29 and 30 are cross sectional views illustrating the position of the several plates and the sheet which is being folded, 55 as illustrated in Figs. 23 and 24, respectively; and
- Fig. 31 is a view similar to Fig. 30, but illustrating the folding of the long sheet shown in Fig. 19.
- 60 As hereinbefore stated, my machine is particularly adapted for folding letter sheets, circulars and similar pieces of paper for insertion into envelopes, and is provided with a substantially flat surface upon which a 65 sheet of paper may be easily placed for fold-

ing, and is provided with a number of relatively movable formers, leaves or plates adapted to receive, hold, and form or fold the sheet. I so arrange the plates upon which the sheet is placed that there is no 70 obstruction above the surface to hinder the placement of the sheet in position. In the machine illustrated in the drawings, this surface is made up of an end former or plate A, and two side plates B and C. All 75 of these plates are mounted upon a suitable box or base D for movement thereon to accomplish the results desired. The plates B and C are arranged parallel with each other and are spread apart a sufficient distance 80 to permit the plate A to be placed between them, and in the operation of folding after the plate A has been placed between the plates B and C these side plates are rotatable over and upon the plate A one in advance of the other. The plate A is mounted in such a manner that it may be moved or rotated away from the upper surface of the box D in such a way as to place its lower surface uppermost and in such position that 85 it extends away from or beyond the plates B and C. In such position it forms a support for the paper sheet, intended to be folded upon the machine, and in combination with the plates B and C and the top 90 of the box forms a substantially level or free surface upon which to place the sheet of paper to be folded. The plate A is so mounted that it can be swung or rotated over and upon the base to a position between 95 the plates B and C and in a plane therewith, as shown in Fig. 2, and when it has reached this position, as stated, the plates B and C are adapted to be rotated to a position above the plate A one in advance of 100 the other. The machine includes an operating lever and mechanism by which these plates are successively placed in position above the middle portion of the base D, as described, when the lever is moved in one 105 direction, and when the lever is moved in the other direction the plates are swung or moved to their starting or original positions each complete movement of the lever serving to fold a sheet of paper which is laid 110 upon the several plates when in their open or original positions.

As shown in Figs. 1 and 3 the plate A preferably occupies an upwardly inclined position before it is swung down, but it will 115 be understood that the angle at which it is disposed may vary through a wide range without departing from my invention, that is, whether level with the plates B and C or elevated at an angle thereto, it with the plates B and C and the top of the base forms a substantially flat surface upon which the sheet of paper to be folded may be placed. The former or plate A is rotatable in one vertical plane, and the side 120 125 130

formers or plates B and C are rotatable in a plane at right angles thereto.

In Fig. 1 I have illustrated by means of the dotted line E, the outline of a sheet of paper which the machine is adapted to fold, this sheet resting upon the plates B and C at one end and upon the plate A at the other end. In Fig. 2 the dotted line E' shows this sheet in the partly folded condition, the portion of the sheet which was supported by the plate A having been folded over upon the portion of the sheet resting upon the plates B and C and in condition to be completely folded by the rotation of the plates B and C over and upon the plate A. The former or plate A is mounted upon a swinging yoke a^1 , which is rotatably mounted upon the forward end of the box and is operatively connected with the operating handle F located at the opposite end of the box by means of which the yoke can be swung from its extended position shown in Figs. 1 and 3 to its closed position, shown in Figs. 2 and 4. The lever is arranged to move transversely of the box, that is, in a plane at right angles to the direction in which the yoke a^1 rotates and the mechanism for connecting the handle F with the yoke a^1 will be fully described hereinafter.

The former A is secured to the middle portion of the yoke a^1 by means of screws or rivets a^2 and when the yoke is in its depressed position the plate A lies substantially in contact with the upper surface of the base or box D, and its secured end is adjacent to the handle or operator F.

The plates B and C, as explained, are arranged at the two sides of the plate A and are mounted to rotate upon axes substantially in alinement with their inner edges. The plates B and C are mounted at one end adjacent to the handle F on short shafts c^1 and b^1 , respectively, and at their opposite ends are provided with extension brackets or arms c^{2a} and b^{2a} respectively each having a pintle c^{3a} in axial alinement with the shaft at the opposite end of the plate and mounted in a rigid bracket c^{3a} secured to and rising from the base.

The length and width of the several plates are determined by the results which are desired, that is, if the machine is designed to fold sheets for what are termed "long envelops" the several plates may be made of considerable length, that is, long enough to fold the sheets on parallel lines to fit the long envelops and the width of the several plates may be arranged likewise, for folding a sheet to the compass desired, either narrower or broader, according to the conditions to be fulfilled.

I provide such an operating connection between the lever F and the yoke a^1 that I am enabled to swing the yoke very rapidly when I rotate it to move the plate A down

upon the base, and consequently the plate in thus moving over and being thrown down upon the base when folding a sheet of paper creates a considerable pressure upon the upper surface of the paper which pressure 70 serves to hold the paper back between the adjacent ends of the plate A and the plates B and C, and form the first fold, which of course is across the sheet. At such time there is no obstruction or projection arranged above the sheet to form this fold, the fold being produced by the rapid movement of the plate A over and upon the base. For the purpose of retaining the sheet in proper relation to the several plates, I provide adjustable end stops d^1 against which one end of the sheet is adapted to be positioned, and an adjustable side stop d^2 against which the one side edge of the sheet is adapted to be positioned. These stops are all adjustable 75 from and toward the center of the base for the purpose of causing the machine to produce the folds at desired positions in the sheet being folded. The method of mounting these stops and their adjustment will be 80 fully described hereinafter.

To further assist in the formation of the first or cross fold, I provide paper stops a^{3a} and a^{3b} which project upwardly from the surface of the plate A, the stop a^{3a} at its 95 outer end adjacent to the yoke a^1 to take the long sheets and the stop a^{3b} spaced inwardly therefrom to take the short sheets. As shown in Fig. 1 the outer end of the sheet E, when the sheet is laid upon the machine, 100 is spaced inwardly from the stop a^{3a} , but it will be understood that as the yoke is swung over there is a relative movement between the sheet and the stop, the sheet sliding out along the plate until the edge contacts with the stop, that is, during the first part of the movement of the yoke. The stop thus assists in the forming of the first fold for immediately the sheet contacts with the stop the forming of the first fold is forced. The 105 exact relation of the position of this first fold to the length of the sheet is controlled by the adjustable stops d^1 which contact with the opposite end of the sheet. The

weight of the yoke A and the plate which 115 it carries and the rapidity with which it moves, produce a certain amount of throw or momentum as the yoke reaches the limits of its movement, and several of the important features in my invention reside in 120 the means which I have devised for overcoming the objectionable effects of the throw of the yoke, and means for reducing the noise incident to its operation as well as incident to the operation of the plates B and C. To assist in overcoming this momentum I make the plate A of resilient or spring metal, and I control its free or inner end a^3 in such a way that this plate is sprung out of its normal parallel relation to the yoke a^1 130

at each limit of its motion in such a direction as to offset or balance the throw of the yoke. For the purpose of assisting in this reduction and noise, I pad the upper surface 5 of the base D by means of a sheet d^3 of felt or other suitable material, which covers most of the upper surface of the base, and for the purpose of providing a smooth surface upon which the plate A is adapted to 10 rest in its final position and upon which it may hold or press the sheet which is being folded, I provide sheet metal bars or strips d^4 , one at each side, and spaced apart so that the plate A will rest upon the flat upper surfaces 15 of these strips when in its depressed position.

As shown in Fig. 13, the padding on the upper face of the base is sufficiently raised at the sides so that the plates B and C cannot 20 touch any metallic portion of the base, but will be received upon these pads. This serves to lessen the noise of operation of the machine. The stops d^1 , as clearly shown in Fig. 4^a, are L-shaped in cross section having 25 a knife edge projection k^1 on their lower ends adapted to project beneath the sheet of paper, which is being placed upon them, and are curved forwardly upon their upper ends k^2 so as to prevent the edge of the 30 paper rising above their tops. Furthermore, to assist this holding of the edge of the sheet in position, I provide the forward face of these stops with slight horizontal serrations or grooves k^3 which engage the edge 35 of the sheet of paper and prevent the edge of the sheet sliding upward along the stop and becoming disengaged therefrom. As shown in Figs. 1 and 3 I provide depressions d^5 in the upper surface of the base adapted 40 to receive the free end of the plate A and forming shoulders d^6 which engage the plate A when the yoke is in its outer position, and which tend to hold the inner end of the plate sprung away from or out of alinement with 45 the yoke. Consequently as the yoke reaches its outer position the spring of the plate A, by the means described, serves to cushion the yoke and bring it easily to a state of rest. As shown in Fig. 4, the relation of the yoke 50 to the base, when in its closed position, is such that the plate A is sprung in the opposite direction, that is, the axis upon which the yoke rotates is so arranged in relation to the upper surface of the box that when 55 the plate A reaches its depressed position, as illustrated in Fig. 4, the yoke stands inclined upwardly at an angle to the base and consequently the plate is pressed against the base with a spring pressure. This depressing 60 of the plate not only serves to assist in stopping the yoke, but also serves to hold the sheet of paper being folded with a slight pressure.

In order to assist in the stopping of the 65 yoke a^1 , as it reaches its depressed portion,

I provide a spring stop d^8 arranged on the base midway between the plates B and C and so positioned that when the yoke is depressed the middle portion of the fixed end of the plate A will strike the spring 70 and the yoke will thus be yieldingly brought to a state of rest. The shafts b^1 and c^1 , which form parts of the plates B and C, are mounted in bearings formed in a 75 box-like extension M of the base provided on the top of the rear end thereof. These shafts are positioned, as shown in the drawings, substantially in alinement with the adjacent horizontal edges of the plate A and the plates B and C, and are adapted, when moved, to rotate the plates B and C from their extended or outer positions which they occupy when at rest to positions over upon and above the plate A when in its depressed position. I secure the plates B and C to 80 their respective shafts in such a manner, that is, more or less removed from the axes of the shafts, that when they are rotated to positions over the middle portion of the base they will be vertically spaced apart 85 sufficient to admit between them one or more sheets of paper for it frequently occurs that it is desired to include card or booklet inserts with the sheets being folded. It will be understood that the relation of the shafts b^1 and c^1 may be varied from the relative positions shown without departing from the spirit of my invention. For the purpose of 90 operating the several plates or formers at their proper times, I arrange the operating lever F at the rear end of the base and adjacent to the housing M. I mount it upon one end of a horizontal rock shaft d^7 carried in suitable bearings in the base and said shaft d^7 is adapted to be rotated back and forth by the transverse movement of the lever F. I provide a second shaft d^8 parallel 95 with the shaft d^7 and geared thereto by means of segmental pinions d^9 and d^{10} .

For swinging or rotating the frame a^1 which carries the plate A, I provide a transverse shaft G mounted in suitable bearings in the base of the machine and, as heretofore described, the frame a^1 is swung over from its outwardly inclined position, as 110 shown in Fig. 3, to its closed position, shown in Fig. 4, in advance of the movements of the plates B and C. For effecting this movement I oscillate the shaft G through a limited arc by means of a crank arm d^{11} secured upon the inner end of the shaft d^7 115 and engaging with a slotted crank arm g^1 secured upon the shaft G. Referring particularly to Fig. 10, it will be seen that I have shown these two members in their related positions, for purposes of illustration, as they appear in the bottom plan view Fig. 5. The crank g^1 is provided with a recess g^2 and a curved arm g^3 . The recess is adapted to receive the outer end of the crank arm d^{11} . The crank arm d^{11} is received in 120

130

the recess g^2 and when rotated in the direction of the arrow (Fig. 9) rotates the shaft G and moves the arm g^1 upwardly until the end of the arm d^{11} disengages the side of the recess and a further movement of the arm d^{11} causes the outer end of the arm d^{11} to sweep along the curved surface g^4 formed on the arm g^1 . The purpose of this is to prevent any backward movement of the arm 5 g^1 and thus lock the frame a^1 during the interval that the end of the arm d^{11} is not in the recess g^2 . When the shaft d^7 is rotated in the opposite direction the outer end of the arm d^{11} sweeps back along the curved 10 surface g^4 , enters the recess g^2 , and rotates the shaft G and arm g^1 back to the position shown in Fig. 9.

The frame a^1 comprises an outer transverse bar a^4 and side bars or rods a^5 . The 20 free ends of these side bars are secured to rotatable members a^6 which are mounted in the side walls of the box adjacent to its forward end. These members a^6 project through the walls of the box and are provided on 25 their inner ends with segmental pinions a^7 . They are mounted for rotation upon bearing rods a^8 secured in position in the box and provided on their outer ends with heads a^9 which secure these members a^6 against 30 movement away from the box. I provide the shaft G with finger gears g^5 , one on each end, adapted to engage with the segmental pinions a^7 , and adapted to rotate the frame a^1 back and forth when the handle F is 35 moved back and forth. By means of this construction I am enabled to swing the frame a^1 from its extended to its closed position in advance of the movement of the plates B and C, that is, the first operation 40 of the movement of the handle F during which time the finger gears c^3 and b^3 are out of engagement with the pinions c^2 and b^2 the frame a^1 is closed down upon the base and is in its closed position at the time 45 that the plate C begins to move. The lateral projection g^4 on the slotted crank g^1 serves, in combination with the crank d^{11} , to lock the frame a^1 in its depressed position during the continuance of the movement of 50 the lever F.

It is my purpose to retain the plates B and C stationary and locked in their outer or normal positions until after the plate A has reached its depressed position and then 55 to rotate them rapidly one in advance of the other over upon the plate A. To accomplish these results I provide the actuating mechanism illustrated. This mechanism comprises the segmental gears d^9 and d^{10} , the gear d^9 being formed upon the hub of the gear c^3 and the gear d^{10} being formed upon the hub of the gear b^3 . A single tooth d^{12a} , which forms a part of the handle F, is made 60 to engage two auxiliary teeth d^{13} and d^{13a} on the gear d^{10} . The tooth d^{12a} is of greater

pitch and diameter than the gear d^{10} and consequently when the shaft d^8 is rotated it is moved at a proportionately higher speed than the shaft d^7 . I provide a locking cam surface d^{12} forming part of the handle F and adapted 70 to engage the single tooth d^{13} of the gear d^{10} during the first portion of the movement of the handle and thus prevent the shaft d^8 rotating. To transmit motion to the shafts b^1 and c^1 for rotating the plates B and C I 75 mount a small segmental pinion c^2 and b^2 upon respective shafts c^1 and b^1 and these are engaged respectively by finger gears c^3 and b^3 mounted respectively upon the shafts d^7 and d^8 , the gear c^3 being mounted freely 80 upon the shaft d^7 and the gear b^3 being secured to rotate with the shaft d^8 . When the handle F is in its first position, as shown in Fig. 6, the finger gears c^3 and b^3 are out of engagement with the pinion c^2 and b^2 but to 85 prevent the plates B and C from being moved at such time I provide a locking arm c^4 and b^4 on respective finger gears c^3 and b^3 which are arranged to engage complementary locking cams c^5 and b^5 on respective pinions c^2 and b^2 . As shown in Figs. 7 and 8^a these locking parts are formed to move out of engagement when the finger gears swing into engagement with the pinions c^2 and b^2 . I so proportion and position the finger gears c^3 and b^3 that the gear c^3 engages with the pinion c^2 before the gear b^3 engages with the pinion b^2 and consequently the plate C is swung or rotated in 90 advance of the plate B. Furthermore, the 100 gear c^3 passes out of engagement with the pinion c^2 at the time that the plate C reaches its folded position and a further movement of the handle F carries the plate B to its final position upon the plate C. It will 105 now be understood that the first part of the movement of the handle F serves to swing down the plate A, both B and C being stationary, and when the plate A has reached its final position the plates B and C are rotated over upon the plate A, the plate C in 110 advance of the plate B, and furthermore that at times when any plate is not moving it is locked in its position.

When the frame a^1 descends upon the 115 base and it strikes the spring d^{76} it would tend to rebound and interfere with the operation of the plates B and C, but once it has descended into contact with the base I lock it in such position for a sufficient time to destroy the rebounding tendency. For this purpose I provide a locking bolt H mounted in the upper part of the housing M and having its rear end h^1 projecting into the path of the lever F, and its forward end h^2 adapted to be projected into the path of a spring latch h^3 carried by the frame a^1 . 120

As best shown in Figs. 1, 2, 15, and 16, the lever F contacts with the rear end of the bolt when at about the middle of its 130

movement at the time that the plate A has reached its lowest position, and pushes the bolt through the housing projecting its forward end into the path of the spring latch 5 h^3 . The latch is beveled in its outer face so that if the bolt is in its way as the frame a^1 descends the latch will spring past the end of the bolt and the bolt will engage the upper edge of the latch and prevent the 10 frame a^1 from rising. I make the rear end of the bolt of considerable length so that the arm F will retain the bolt at its inner position long enough to prevent the plate A rising and interfering with the folding movements of the plates B and C. The bolt H is 15 normally held at the rearward limit of its movement and out of the path of the spring latch h^3 , by a small spring h^4 secured within the housing M.

20 As shown in Fig. 13, by means of the dotted line which indicates the section of the sheet being folded at the time that the plate A descends upon the base, the middle portion of the sheet lies beneath the plate and 25 the side portions lie above the plates B and C in such position that as the plates B and C are rotated over and upon the plate A to be carried with these plates and folded upon the plate A as indicated in Fig. 14. Consequently 30 at the completion of the folding movement of the several plates the sheet of paper is wrapped around the plate A and lies between the plates A, B, and C, but at this time the edges of the folds are not 35 creased and should the plates be returned to their original positions the sheet would not be permanently folded. To complete the folding of the sheet I provide means for creasing the folds so that the sheet will be 40 retained in its folded condition after removal from the machine.

For this purpose I provide creasers arranged in alignment with the folded edges of the sheet, that is, in substantial alignment 45 with the edges of the several plates when they are in folded position and adapted as the sheet is withdrawn longitudinally to progressively crease the folded edges thereof. I arrange one creaser in line with each edge; 50 and each consists of a light spring a^{10} secured at one end, with its free end projecting beneath the outer end of the bracket c^{84} that carries the outer bearing of one of the side plates. This spring bears upon the 55 underside of the bracket, as clearly shown in Figs. 12 and 12^a and the bracket is beveled inwardly and upwardly in order that the folded sheet will be guided into position between the bracket and spring as the sheet 60 is withdrawn from its folded position.

The center portions of the outer ends of the three plates, A, B, and C, are cut out, providing recesses or openings aa , bb , and cc , respectively, at their free ends to permit 65 the grasping of the folded sheet so that it

may be withdrawn lengthwise from the several plates. I make use of this feature to crease the transverse folds, or rather the first or original fold produced by the swinging down of the plate A, as the thumb or 70 finger of the operator in grasping the sheet presses the several layers together and thus makes the folds permanent, or, in other words, creases them. In addition to this, I make the creaser feet a^{12} wide enough to 75 overlap this end portion of the folded sheet and as the sheet is withdrawn the first action of the creasers is to crease the outer parts of the end fold, the middle portion thereof being creased by being grasped. 80

For convenience in grasping the end of the folded sheet to withdraw it from its folded position, I provide the central part of the base beneath the overlapped outer ends of the plates with a large recess d^{44} 85 to permit the fingers to be inserted beneath the sheet.

As indicated in Fig. 8, I may connect a link L to the handle F by a pivot l^1 for the purpose of operating the machine, by 90 power rather than by hand, the link or connection being operated by some suitable power mechanism.

As suggested hereinbefore, the stops d^1 and d^2 are adapted to retain the sheet in 95 its desired position and are made adjustable so that the operator may control the folding of the sheet in the exact relation desired. The stops d^1 , against which the end of the sheet is adapted to be placed, are mounted 100 upon horizontally arranged U-shaped bars d^{14} , the upper member d^{15} of which lies parallel with the upper face of the base and the lower member d^{16} enters the base through its rear wall. The inner ends of 105 these U-shaped bars are joined to a cross bar d^{17} mounted within the box. This cross bar is carried upon a screw shaft d^{18} which projects through the rear wall of the box and is held against endwise movement, the 110 outer end of the shafts being provided with a knurled head d^{19} . The bar d^{17} is provided with a threaded hole d^{20} to receive the screw shaft d^{18} and by means of which the bar d^{17} is moved back and forth within 115 the box carrying the stops d^1 with it. To hold the bar d^{17} and the stops d^1 in proper alignment, I provide a second bearing d^{21} on the bar d^{17} for the shaft d^{18} and spaced from the threaded hole d^{20} . The inner end 120 of the screw shaft is mounted for rotation in a bearing provided in a bracket d^{22} in which the inner ends of the shafts d^1 and d^2 are also mounted. Likewise the stop d^2 is carried upon two U-shaped rods d^{23} which 125 in like manner with the rods d^{14} enter the side of the base and are mounted upon a cross bar d^{24} which is adjustable transversely of the box by means of an adjusting screw d^{25} . 130

At times it is desirable to fold up a sheet which is longer than the combined width of the plates A, B, and C, and which, when placed in position upon the machine, with 5 one end against the stop d^2 , projects over the base of the machine at the opposite side. In folding such a sheet it is possible that the projecting end of the sheet will drag sufficiently to prevent the accurate folding 10 of the sheet, and to prevent this action I provide a laterally extending shelf J upon the base, located at the side opposite to the stop d^2 , and I provide an auxiliary folding plate j^1 secured to the adjacent side bar a^3 15 of the frame a^1 . This auxiliary plate j^1 is yieldingly resilient, similar to the plate A and acting in cooperation with plate A helps to fold the overhanging outer end of the sheet. I make this auxiliary plate of 20 such strength that it does not retain the sheet upon the shelf J with sufficient friction to prevent its withdrawal when the adjacent side plate C tends to fold the sheet beneath the plate B. I provide an opening j^2 in 25 the shelf J to receive the free end j^3 of the auxiliary plate j^1 , and this plate acts similarly to the plate A in yieldingly stopping the frame a^1 at each limit of its movement.

Turning our attention now to Figs. 17 to 30, inclusive, I have here illustrated some of the many ways of folding sheets of paper of which my machine is capable. The shaded portion in each instance shows the 35 final size or area of the completely folded sheet. For instance, Fig. 17 shows a simple two-fold, that is, the sheet is folded upon a longitudinal medial line m^1 and has but one creased fold. For such a purpose the sheet is laid upon the machine with one end upon 40 the plate B and the other extending between the plates B and C, as shown in Fig. 23. The plate A is then brought down upon the sheet to hold it, and the plate B is then rotated over and upon the plate A. In all of 45 these foldings it will be understood that in the withdrawal of the sheet from the folded position between the plates, the folds are creased to permanently preserve the sheet in its folded condition. Fig. 18 illustrates 50 what may be termed the two-fold sheet folded at the dotted lines m^1 and m^2 , that is, the sheet is of such a length that when laid upon the machine it extends across and over the plates B and C, but does not extend up 55 onto the plate A. The plate A is then brought down upon the sheet between the plates B and C, as shown in Fig. 24, and the plates B and C are rotated over and upon the plate A, as shown in Fig. 30. 60 Fig. 19 illustrates what may be termed the "four-fold", that is, where the sheet is folded upon three lines m^1 , m^2 and m^3 . In this instance the sheet is longer than the extreme width of the plates B and C and 65 when placed in position projects beyond the

plate C, but as the plate C is rotated over upon plate A in advance of plate B, plate C carries the long end of the sheet beneath plate B and plate B thus completes the last or third fold m^4 of the sheet, folding the 70 sheet as clearly shown in Fig. 31 upon three lines. Figs. 20, 21, 22, 26, 27, and 28 illustrate the folding of sheets which are longer than the length of the plates B and C on line m^5 and which, when placed in position 75 upon the machine, extend up upon the plate A. The first operation in the folding of these sheets, as has been fully described, is that of folding the long end of the sheet down upon the end which lies upon the 80 plates B and C by means of the plate A and thereafter the sheet is folded in the same manner as that described in relation to Figs. 17, 18, and 19.

I do not herein claim the novel method of 85 folding sheets of paper, but refer instead to my copending application, Serial No. 850,491, of even date herewith.

As many modifications of my invention will readily suggest themselves to one skilled 90 in the art, I do not limit or confine my invention to the specific structures herein shown and described.

I claim:—

1. In a paper-folding machine provided 95 with a substantially flat surface for receiving a sheet of paper to be folded, a relatively thin flat holder having parallel side edges and of smaller area than the sheet to be folded adapted to be positioned over the 100 paper to prevent the direct movement of the paper away from said surface, rotatable formers adjacent to said holder, adapted to be positioned beneath the unheld portions of the paper and to be rotated over said parallel edges and upon and in parallel relation to the holder to fold the paper thereupon, and creasers in line with said parallel edges of the holder for creasing the edges of the 105 folds as the folded sheet is withdrawn.

2. In a paper folding machine provided 110 with a substantially flat surface adapted to receive a sheet of paper to be folded, a relatively thin obstruction member having substantially parallel side edges movable toward and away from said surface and adapted to be positioned substantially in contact with and above a portion of the sheet to be folded, and extending from edge to edge thereof, rotatable formers arranged 115 at the parallel sides of said obstruction member adapted to lift the unobstructed portions of the sheet and form them over and upon said obstruction, and yielding pressers arranged in alinement with the parallel edges of said member adapted to crease the edges of the folded sheet as it is withdrawn from the machine.

3. In a paper folding machine a fixed support and a movable support together form- 120

ing a surface to receive a sheet of paper to be folded, means for moving said movable support over and upon and into substantial contact with said fixed support for folding a sheet of paper, said movable support being of less width than the sheet of paper and adapted, in its final position, to hold the folded sheet upon said fixed support, formers adjacent to the final position of 10 said movable support adapted to be rotated over and upon and into substantially parallel relation with said movable support.

4. In a paper folding machine a fixed paper support and a movable paper support 15 together forming a surface to receive a sheet of paper to be folded, means for swinging said movable support over, upon and into substantial contact with said fixed support for folding a sheet of paper, said movable support being of less area than the sheet of paper and adapted, in its final position, to prevent the direct movement of the folded sheet from said fixed support, a rotatable plate adjacent to the final position of said 20 movable support adapted to be rotated over and upon the movable support, when it is in final position, to fold the partly folded sheet at right angles to the first fold.

5. In a paper folding machine a fixed 25 paper support and a movable paper support together forming a substantially continuous surface to receive a sheet of paper to be folded, means for swinging said movable support over, upon and into substantial contact with said fixed support for folding a 30 sheet of paper, said movable support having substantially parallel side edges, being of less area than the sheet of paper and adapted, in its final position, to hold the folded sheet upon said fixed support, a rotatable plate adjacent to the final position of said 35 movable support adapted to be rotated over and upon the movable support, when in its final position, to fold the partly folded sheet 40 at right angles to the first fold, and a fold creaser in line with the adjacent edges of the movable support and the plate.

6. In a paper folding machine a base member having a substantially flat surface and 45 a rotatable plate mounted thereon, a relatively thin paper holder having parallel side edges adapted to be positioned over said base adjacent to said rotatable plate, and means for rotating said plate over and upon 50 the holder to fold a piece of paper, and a yielding creaser arranged in alinement with the adjacent edges of said holder and plate and adapted to crease the edge of the folded paper as same is withdrawn from the machine.

7. In a paper folding device, a base provided with a flat surface and a movable member having a substantially flat surface rotatable into contact therewith, rotatable 55 plates mounted upon the base adapted to be

rotated over and upon the movable member, after the same has been brought to rest, to fold a sheet of paper, and fold creasers arranged in alinement with the respective edges of the movable member and rotatable 70 plates.

8. A paper folding machine having a substantially flat surface to receive a sheet of paper to be folded, a movable member forming part of said surface adapted to be 75 rotated into parallel relation to the fixed portion of said surface to fold a sheet of paper, said member being of less width than the paper to be folded, rotatable formers carried by said machine, separated sufficiently to receive said movable member and adapted to be rotated over and upon said member after it has reached its final position, an operating lever adapted to move said member into its final position, means 80 permitting the forward movement of the lever after said member has reached its final position, and means operatively connecting said lever with said formers for rotating them after said member has been 85 brought to a state of rest.

9. A paper folding machine having a substantially flat surface to receive a sheet of paper to be folded, a movable member forming part of said surface and adapted to be 90 rotated into parallel relation to the fixed portion of said surface to fold a sheet of paper, said member being of less width than the paper to be folded, rotatable formers carried by said machine, separated sufficiently to receive said movable member and adapted to be rotated one in advance of the other over and onto said member after it had reached its final position, an operating lever for moving said member into its final 95 position, connections between said lever and said member permitting the forward movement of the lever after said member has reached its final position, and holding said member locked, and means operatively connecting said lever with said formers for rotating them after the member has been 100 brought to a state of rest.

10. A paper folding machine having a fixed and a relatively movable member together forming a substantially flat surface for receiving a sheet of paper to be folded, stops arranged upon the fixed member for retaining the paper in position, said movable member being adapted to be rotated 115 over and upon the fixed member to fold a sheet of paper, and rotatable plates carried by said fixed member adapted to be rotated over and upon said movable member after it has reached its final position to complete 120 the folding of the paper.

11. A paper folding machine having a fixed and a relatively movable member provided with surfaces which together form a substantially flat surface for receiving a 125

- sheet of paper to be folded, adjustable stops arranged upon the fixed member for retaining the paper in position, said movable member being adapted to be rotated over and 5 upon the fixed member to fold the sheet of paper, rotatable plates carried by said fixed member adapted to be rotated over and upon said movable member after it has reached its final position, and yielding members arranged to crease the folds of the sheet as it 10 is withdrawn from the machine.
12. A paper folding machine having a fixed and a relatively movable member provided with surfaces which together form a 15 substantially flat surface for receiving a sheet of paper to be folded, adjustable stops arranged upon the fixed member for retaining the paper in position, said movable member being adapted to be rotated over and 20 upon the fixed member to fold the sheet of paper, said movable member being provided with a fixed stop coacting with said adjustable stops to control the folding of the sheet of paper, rotatable plates carried by said 25 fixed member adapted to be rotated over and upon said movable member after it has reached its final position.
13. In a machine for folding a sheet of paper, a base having a substantially level 30 surface and a rigid rotatable frame carried by said base and provided with a substantially flat spring plate, the plate and the flat surface of the base together forming a sheet receiving surface, said frame being adapted 35 to be rotated relatively to the base to fold a sheet of paper, said plate being adapted to be sprung out of its normal position at each limit of the movement of said frame to cushion the blow thereof and to exert a pressure 40 upon the paper when in contact with the base.
14. In a machine for folding a sheet of paper, a base having a substantially level top 45 surface and a rigid rotatable frame carried by said base and provided with a substantially flat spring plate having parallel side edges, the plate and the flat surface of the base together forming a sheet receiving surface, said plate being adapted to be rotated 50 toward and upon the base to fold a sheet of paper and being adapted to be sprung out of its normal position at each limit of the movement of said frame to cushion the blow thereof and to exert a pressure upon the 55 paper when in contact with the base, and a folding plate mounted on the base at each side of the final position of said spring plate adapted to be rotated over and upon said spring plate to complete the folding of a 60 sheet of paper.
15. In a paper folding machine, a base having a substantially flat surface, a frame rotatably mounted on said base, a flat pressure plate carried by the frame, a lever operatively connected with the frame for rotat- 65
- ing it into substantially parallel relation to the base and said plate into contact with the surface of the base, a crank connected to the lever and a slotted arm connected to the frame, said crank being adapted to operate 70 in said slot to move the frame and to be withdrawn from the slot as the plate contacts with the base, and a locking projection on said slotted arm adapted to contact with said crank to hold said plate in contact 75 with the base as said lever moves forward to complete the folding of the sheet.
16. In a paper folding machine having a substantially flat surface upon which the paper is to be folded, a rotatable member 80 adapted to be rotated down and into contact with said surface, folding plates carried on said machine adapted to be rotated over and upon said member after it has reached said surface, an operating lever, a make-and-break connection between said operating lever and the rotatable member, permitting the lever to move forward after the rotatable member is in its final position, and make-and-break connections between said lever 85 and said folding plates for rotating them, one in advance of the other over upon said rotatable member.
17. In a paper folding machine a base having a substantially flat surface, and a 90 rotatable member mounted upon said base having a flat surface adapted to be rotated down into contact with the surface of the base, an operating lever adapted to move said rotatable member, a pin-and-slot connection between said lever and member permitting the lever to move forward after the member has reached its final position, and means for locking said member in its final 95 position.
18. In a paper folding machine a base having a substantially flat surface, and a rotatable member provided with a centrally arranged plate adapted to be rotated into contact with the flat surface to fold a sheet 100 of paper, a lever for operating said movable member, and a locking member operated by said lever adapted to hold said rotatable member in its depressed position.
19. In a paper folding machine a base 115 having a substantially flat surface, a rotatable member carried by the base and provided with a centrally arranged plate adapted to be rotated into contact with the middle portion of said flat surface to fold a sheet 120 of paper, a lever for operating said movable member, a locking member operated by said lever adapted to hold said rotatable member in its depressed position, and plates mounted on said base adapted to be rotated over and 125 upon said centrally arranged plate to fold a sheet of paper.
20. In a paper folding machine a base provided with a substantially flat surface and a rotatable member mounted on the base 130

carrying a substantially flat plate, the surface and plate together being adapted to receive a sheet of paper to be folded, means for swinging said rotatable member to bring 5 said plate into parallel relation to and upon said flat surface for folding a sheet of paper, a spring catch carried by said movable member, a lever for operating said movable member, and a bolt carried by said base operable by said lever to be projected into the 10 path of said spring catch for retaining said movable member in its depressed position.

21. In a paper-folding machine a fixed member having a substantially flat surface 15 and a member carrying a flat plate rotatably mounted upon said fixed member, and movable to position said plate upon said flat surface, said plate being narrower than the fixed member, rotatable formers carried by 20 the fixed member adapted to be rotated over and upon said plate after the same has reached its final position, and fold creasers positioned in alinement with the edges of said movable member, for creasing the folds 25 as the folded sheet is withdrawn from the machine.

22. In a paper folding machine a base member having a substantially flat surface and a member carrying a flat plate rotatably 30 mounted upon said base and movable to position said plate in contact with said surface, said plate being narrower than the fixed member, rotatable formers carried by the fixed member, adapted to be rotated over 35 and upon said plate after the same has reached its final position, and fold creasers carried by the base in alinement with the adjacent side edges of said formers for creasing the folds of a sheet as it is withdrawn from the machine.

23. In a paper folding device a base having a substantially flat surface and rotatable formers thereon spaced apart, a frame carried by the base having a forming plate 45 adapted to be rotated down and upon said base between the formers, said formers being adapted to be rotated over and upon said plate after the plate has reached its final position and spring pressers carried by said 50 base in alinement with the edges of said plate and adapted to crease the edges of the folded paper as it is withdrawn from the machine.

24. In a paper folding machine, three 55 plates arranged substantially in a single plane and side by side, their adjacent edges being substantially parallel, the middle plate being adapted to be positioned above a sheet of paper to be folded and the outer plates 60 arranged below the paper to be folded and rotatable over and upon the middle plate, and yieldable means for creasing the folded edges as the folded sheet is withdrawn from the machine.

65 25. In a paper folding machine three

plates arranged substantially in a single plane and side by side, the adjacent edges being substantially parallel, the middle plate being adapted to be positioned above the paper to be folded and the outer plates arranged below the paper to be folded and rotatable over and upon the middle plate, to fold a sheet of paper, the three plates being provided at their free ends with spaced 70 prongs providing a free open space to permit the grasping of a folded sheet for withdrawal from the machine, and yielding pressers arranged in alinement with said adjacent parallel edges for creasing the folds 75 as the sheet is withdrawn from the machine. 80

26. In a paper folding machine, two oppositely disposed rotatable plates spaced apart and normally lying in the same plane, a third plate hingedly mounted upon said machine adapted to be brought down substantially into the plane of said rotatable plates and between same, and means for rotating said rotatable plates over and upon the middle plate one in advance of the other. 85

27. In a paper folding machine, two oppositely disposed rotatable plates spaced apart and normally lying in the same plane, a third plate hingedly mounted upon said machine adapted to be brought down into the plane of said rotatable plates and between same, means for rotating said rotatable plates over and upon the said third plate, one in advance of the other, and yielding pressers arranged in alinement with the longitudinal edges of said third plate to 90 crease the edges of the folds as the paper is withdrawn from said third plate. 95

28. In a paper folding machine, three substantially flat movable folding members arranged to receive a sheet of paper to be 100 folded and to be moved successively to fold a sheet, one of said members being movable to a position between the other two and upon a sheet to be folded, a single operator operatively connected with all of said members, 105 and locking means retaining two of the members in their sheet receiving positions during the movement of the other member to its sheet-holding position.

29. In a paper folding machine, three 110 substantially flat movable folding members arranged to receive a sheet of paper to be folded and to be moved successively to fold a sheet, one of said members being movable to a position between the other two and upon a sheet to be folded, a single operator operatively connected with all of said members, locking means retaining the two outer members in their sheet receiving positions until the middle member has been moved to its 115 sheet-holding position, and means locking the middle member in its sheet-folding position during the folding movements of the two other members. 120

30. In a paper folding machine a support 125

- and a relatively movable support together forming a surface to receive a sheet of paper to be folded, means for moving said movable support over and upon and into substantial contact with said first mentioned support for folding a sheet of paper, said movable support being of less width than the sheet of paper and adapted, in its final position to hold the folded sheet upon said first mentioned support, formers adjacent to the final position of said movable support adapted to be rotated over and upon and into substantially parallel relation with said movable support.
31. In a paper folding machine a paper support and a relatively movable paper support together forming a surface to receive a sheet of paper to be folded, means for swinging said movable support over, upon and into substantial contact with said first mentioned support for folding a sheet of paper, said movable support being of less area than the sheet of paper and adapted, in its final position, to prevent the direct movement of the folded sheet from said first mentioned support, a rotatable plate adjacent to the final position of said movable support adapted to be rotated over and upon the movable support, when it is in final

position, to fold the partly folded sheet 30 at right angles to the first fold.

32. A paper folding machine having a substantially flat surface to receive a sheet of paper to be folded, a movable member forming part of said surface adapted to be rotated into parallel relation to the other portion of said surface to fold a sheet of paper, said member being of less width than the paper to be folded, rotatable formers carried by said machine, separated sufficiently 35 to receive said movable member and adapted to be rotated over and upon said member after it has reached its final position, an operating lever adapted to control the movement of said member into its final position, means permitting the forward movement of the lever after said member has reached its final position, and means whereby said lever controls the rotation of said formers after said member has been brought 40 to a state of rest.

In testimony whereof, I have hereunto set my hand, this 8th day of July, 1914, in the presence of two subscribing witnesses.

WALTER E. AMBERG.
